UNITED STATES PATENT OFFICE.

CURTIS A. SQUIRES AND ALBERT E. HUMPHREY, OF LYNDONVILLE,
VERMONT.

DOOR-HANGER.

No. 835,372.

Specification of Letters Patent.

Patented Nov. 6, 1906.

Application filed January 20, 1906. Serial No. 297,027.

To all whom it may concern:

Be it known that we, CURTIS A. SQUIRES and ALBERT E. HUMPHREY, citizens of the United States, residing at Lyndonville, in the county of Caledonia and State of Vermont, have invented certain new and useful Improvements in Door-Hangers, of which the following is a specification.

The present invention relates to an improved device for the mounting of sliding doors, and is especially designed for use in connection with the doors upon freight-cars or other doors where the tracks are exposed and are liable to become obstructed by deposits of cinders and dirt.

The object of the invention is to provide a device of this character which will reduce the friction to a very small amount, so that heavy doors may be operated with comparatively slight effort.

A further object of the invention is to so construct the track that it will be impossible for dirt to accumulate therein to a sufficient extent to interfere with the free operation of the door.

For a full description of the invention and the merits thereof and also to acquire a knowledge of the details of construction of the means for effecting the result reference is to be had to the following description and accompanying drawings, in which—

Figure 1 is a side view of a portion of a car and shows a door mounted in accordance with my invention. Fig. 2 is a transverse sectional view through the upper portion of a door. Fig. 3 is a detail perspective view of the track, and Fig. 4 is a similar view of the hanger.

Corresponding and like parts are referred to in the following description and indicated in all the views of the drawings by the same reference characters.

The numeral 1 designates the side of a car, and 2 the door, which may be constructed in any suitable manner. The track 3 is secured to the side of the car immediately over the door-opening and is of such a length as to extend to one side of the door for a distance equal to the width thereof. This track 3 comprises, essentially, two flanges which are disposed at approximately right angles to each other. One of the flanges 4 is employed in securing the track to the car, while the opposite flange 5 projects outwardly and

has approximately the form of a V-shaped trough. This trough is formed with two oppositely-inclined sides and is provided along its base at suitable intervals with a series of openings 6. It will thus be seen that any cinders or dirt which may fall upon the track 60 will be deflected to the bottom thereof by means of the inclined sides and will finally escape through the openings 6. This feature is particularly valuable where the device is used upon railroad-cars, since they are exposed to conditions very favorable for the collection of cinders. The hangers 7 are somewhat similar in construction to the track 3, and one of them is preferably secured to each end of the door, as shown in the drawings. These hangers comprise two flanges at approximately right angles to each other, one of which, 8, is secured to the outside face of the door, while the opposite flange 9 projects inwardly and has the form 70 of an inverted-V-shaped trough. The ends of these troughs are closed at 10, and a number of balls 11 are located between the troughs and the track 3. Owing to the fact that the hangers and the track are both formed with angular troughs within which the balls 11 operate, it will be apparent that the amount of friction will be reduced to a minimum, since each of the balls can come into contact with either the hanger or the 85 trough at only two points, and the surface of contact when the door is operated will be two minor circles upon the balls. This construction has the double advantage of reducing the friction to a very small amount and 90 also of preventing the accumulation of cinders or dirt in the track.

Having thus described the invention, what is claimed as new is—

1. In a device of the character described, the combination of a track in the form of a V-shaped trough, said trough being provided with a series of openings in its under side, means for supporting the track, a door, a hanger secured to the door and comprising an inverted-V-shaped trough located over the track, and a series of balls interposed between the hanger and the track.

2. In a device of the character described, the combination of a track comprising two flanges at approximately right angles to each other, one of said flanges being employed to secure the track in position while the oppo-

site flange is in the form of a V-shaped trough, said trough being provided with a series of openings in its under side, means for supporting the track, a sliding door, a hanger at each end of the sliding door, said hangers comprising two flanges at approximately right angles to each other, one of the flanges being secured to the door, while the opposite flange is in the form of an inverted-V-shaped trough having its ends closed and projecting

inwardly over the track, and a series of balls interposed between the hangers and the track.

In testimony whereof we affix our signatures in presence of two witnesses.
